(57) **CLAIM**

The ornamental design for a model vehicle wheelie bar side component, as shown and described.

DESCRIPTION

FIG. 1 is an upper, right, front perspective view of a model vehicle wheelie bar side component showing our new design;

FIG. 2 is a front elevation view thereof;

FIG. 3 is a rear elevation view thereof;

FIG. 4 is a left-side elevation view thereof;

FIG. 5 is a right-side elevation view thereof;

FIG. 6 is an upper plan view thereof;

FIG. 7 is a lower plan view thereof; and,

FIG. 8 is a lower, left, rear perspective view of the model vehicle wheelie bar side component.

In the drawings, the broken lines illustrate portions of the model vehicle wheelie bar side component that form no part of the claimed design.

1 Claim, 5 Drawing Sheets
